(57) **CLAIM**

The ornamental design for a front gate with fence, as shown and described.

DESCRIPTION

FIG. 1 is a perspective view of a front gate with fence in a closed gate position, showing my new design;

FIG. 2 is a front elevation view thereof;

FIG. 3 is a back elevation view thereof;

FIG. 4 is a right side elevation view thereof, the left side elevation view being a mirror image thereof;

FIG. 5 is a top plan view thereof;

FIG. 6 is a perspective view of the front gate with fence in a open gate position;

FIG. 7 is a front elevation view thereof;

FIG. 8 is a back elevation view thereof;

FIG. 9 is a right side elevation view thereof, the left side elevation view being a mirror image thereof; and,

FIG. 10 is a top plan view thereof.

The broken lines depict portions of the article that form no part of the claimed design.
